UNITED STATES PATENT OFFICE.

GEORGE E. FARLINGER, OF DETROIT, MICHIGAN, ASSIGNOR TO ANGUISH MANUFACTURING COMPANY, OF DETROIT, MICHIGAN, A CORPORATION OF MICHIGAN.

RADIATOR.

1,076,203.

Specification of Letters Patent.

Patented Oct. 21, 1913.

Application filed February 23, 1912. Serial No. 679,240.

To all whom it may concern:

Be it known that I, GEORGE E. FARLINGER, a citizen of the United States, residing at Detroit, in the county of Wayne and State 5 of Michigan, have invented certain new and useful Improvements in Radiators, of which the following is a specification.

The invention relates to improvements in radiators of the type employed in automobiles, and which are composed of one or 10 more sections formed of spaced plates having a plurality of air passages extending therethrough.

The invention resides in the novel formation 15 and construction of the air passages whereby the desired cooling surface is provided and the proper spacing of the plates permitted.

In the drawings,—Figure 1 is a front elevation of a radiator embodying my invention; Fig. 2 is a vertical, sectional view; Fig. 3 is an enlarged, fragmentary, sectional view through one of the radiator sections; and Figs. 4 and 5 are fragmentary 25 side elevations of the coöperating plates of one of the sections.

My improved radiator is composed of a plurality of sections, four being shown in the construction illustrated in the drawings. 30 Each of these sections includes coöperating spaced plates 1 and 2 of suitable sheet metal, the plates preferably being of sufficient size to extend throughout the width and height of the radiator. The plate 1 is provided 35 with a plurality of collars 3 stamped thereout, while the plate 2 has coöperating collars 4 similarly formed. The latter collars are of a size to telescope with the free ends of the collars 3, and when the coöperating 40 members 3 and 4 are telescoped, passages 5 are formed through the section.

In order to obtain the greatest cooling efficiency the passages must be of a size sufficient to permit free passage of air there- 45 through, but on the other hand, the openings cannot be too large or the amount of cooling surface is reduced. In other words, the smaller the passage the greater the amount of metal which is exposed to the atmosphere. 50 Therefore, practically a certain size opening is required in order to produce a section having maximum cooling efficiency. However in stamping out the collars there is a limit to which the metal can be drawn, and with 55 openings of suitable size the length to which

the collar may be drawn is less than the distance which it is desired to have the plates spaced, since if the plates are in too close proximity, sufficient free passage of the water through the section will not be permitted. In order to obtain the desired spacing for the plate members a bearing is formed on one of the coöperating telescoping collars intermediate the ends and the coöperating collar engages this bearing. In 60 the drawings (see Fig. 3) this bearing is shown as an annular shoulder 6 and the end of the other coöperating collar as seating upon this shoulder. This materially increases the spacing of the plates over that 65 which could be had if the collars completely telescoped.

The forming of the shoulder 6 on the collar is another highly advantageous feature. Thus it is desirable to have the telescoping 70 portions of the collar circular, so as to obtain a tight joint, but dealers often prefer the openings in the outer face of the front radiator section to be of such a contour as to produce a square or hexagonal effect. 75 With the construction hereinbefore described the portion 7 of the collar 3 which telescopes with the collar 4 is made circular, while the portion 8 intermediate the inner end of the collar 3 and the annular shoulder 80 6 may be given any desired configuration, the portion 8 being shown hexagonal in the drawing—see Fig. 1. In making the sections, after the collars are telescoped, the joints between the collars are completely 85 closed as by dipping the section in solder in the usual manner. The side edges of the sections may be closed in any desired way, members 23 preferably being employed for 90 this purpose. Likewise as far as the invention claimed herein is concerned, the sections 95 may be attached to the tank in whatever manner desired.

What I claim as my invention is:—

1. A hollow radiator section, comprising 100 two spaced plate portions each formed from flat metal having a plurality of collars struck out therefrom, the collars on the one section telescoping with the collars on the other, one member of each telescoping pair 105 being provided intermediate its ends with a shoulder, forming a spacing bearing with which the other member engages.

2. A hollow radiator section, comprising 110 two plate members each formed from a flat

sheet of metal having a plurality of collars struck out therefrom, the collars on the one section telescoping with the collars on the other and being provided with annular shoulders intermediate their ends, forming

5 bearings upon which the free ends of the collars of the last-mentioned section rest.

In testimony whereof I affix my signature in presence of two witnesses.

GEORGE E. FARLINGER.
